GAS-LIFT PUMP

Granville S. Knox, Los Angeles, Calif., assignor of
one-half to B. E. Ahlport, La Canada, Calif.

Application November 15, 1935, Serial No. 49,942

37 Claims. (Cl. 103—234)

This invention relates to pressure actuated pumps used in lifting liquids from wells, and more particularly to pumps using natural gas, compressed air, steam or other gaseous substance under pressure as the actuating medium.

An object of the invention is to provide a durable mechanism for lifting liquids containing abrasive or corrosive matter out of wells without the use of reciprocating plungers or sucker rods which would be damaged by the abrasive or corrosive elements in the liquid.

Another object is to provide a method of producing oil from oil wells, which method will effect an economy in the amount of natural gas produced with the oil in order to conserve the gas, thereby maintaining the pressure in the formation and extending the period of economical oil production.

Another object is to provide a pressure actuated mechanism for lifting liquid from wells that responds to varying well conditions to automatically so regulate the rate at which liquid is lifted as to cause the mechanism to operate at best efficiency at all times.

Another object is to provide a small compact gas-lift pump unit which may be readily inserted in and removed from standard size well tubing or casing.

Still another object is to provide a gas-lift pumping unit which comprises few, simple and compact parts which cannot easily get out of order, thus increasing the efficiency of the unit and reducing the cost of manufacturing it and of maintaining it in operating condition.

Other more specific objects and features of the invention will be apparent from the detailed description with reference to the drawings which follow.

Oil has been usually lifted from wells by reciprocating plunger pumps located deep in the well and actuated by a string of sucker rods extending up through the well to the surface. Such pumps have given satisfactory results in shallow wells producing clean oil, but they are a constant source of trouble in deep wells, wells with crooked bores and wells producing abrasive and corrosive elements with the oil. In deep wells the sucker rod string is greatly over-loaded and is a constant source of trouble due to the stretching and breaking of the rods. In wells having crooked bores excessive wear takes place on both the sucker rods and well tubing, necessitating costly replacement. In wells containing abrasive or corrosive elements, or both, the pump plunger and barrel quickly wear out or the close fitting

plunger freezes in the barrel and becomes inoperative.

To avoid the objectionable features of plunger pumps actuated by sucker rods, gas-lift pumps of various types have been employed to some extent. They have been fairly satisfactory in wells having relatively high oil levels and which produce very little water with the oil. However, when the oil level in the well becomes low, ordinary gas-lift methods become increasingly inefficient or fail to produce at all. When considerable water is present with the oil, the use of ordinary gas-lift methods causes a tight oil water emulsion which requires special and somewhat expensive methods of treatment to obtain a separation of the oil and water at the surface.

A gas-lift pump in accordance with my present invention operates without sliding plungers or barrels and without any movable mechanical elements connecting the pump in the well to the surface. Furthermore, although my pump employs gas pressure for its operation, the gas is not mixed with the liquid pumped and where the liquid contains oil and water it does not emulsify the oil and water. Furthermore, my pump operates as a pressure displacement pump in much the same manner as a plunger displacement pump and it is not necessary to satisfactory operation to have a high liquid level in the well. As a result, my pump combines to a large extent the desirable features of the ordinary gas-lift pump and the reciprocating plunger pump while avoiding many of the undesirable features of both.

In the drawings:

Fig. 1 is a schematic diagram showing one pumping unit in accordance with my invention installed in a well;

Fig. 2 is a schematic diagram of a different form of unit in accordance with the invention;

Fig. 3 is a schematic diagram illustrating one method of employing the units shown in Figs. 1 and 2 in a well;

Fig. 4 is a schematic diagram illustrating another method of employing my unit in a well;

Fig. 5 is a schematic diagram illustrating still another method of employing my unit in a well;

Fig. 6 is a schematic diagram of a modification of the unit shown in Fig. 1;

Figs. 7 and 8 are vertical sectional views showing in detail the actual construction that may be employed in a unit of the type disclosed schematically in Fig. 1;

Fig. 9 is a vertical sectional view showing the actual construction that may be employed in a

unit of the type shown schematically in Fig. 2; and

Fig. 10 is a sectional detail view of a needle valve that may be employed with a unit in accordance with my invention in some installations.

Referring to Fig. 1, a pumping unit 1, in accordance with the invention, is shown inserted upon tubing string positioned in a well casing 4. The portion 5 of the tubing string above the unit 1 extends to the surface and connects at the surface to a discharge pipe 6 adapted to receive gas and liquid and discharge them at low pressure. Thus the pipe 6 may discharge into an open receptacle or it might be connected to a suction pump which maintains a pressure less than atmospheric in the pipe 6. That portion 7 of the tubing extending below the unit 1 extends below the level of the fluid in the casing 4, which fluid is to be pumped. The upper end of the casing 4 is preferably closed to retain gas pressure therein. This gas pressure may result from the natural gas production of the well or it may be artificially created by pumping gas into the casing as through a pipe 8 connecting to the casing at the surface.

The unit 1 comprises a body member of lateral dimensions less than the inner diameter of the casing 4 which defines therewithin a passage 9 communicating through a standing valve 10 with the tubing 7 below the unit. The upper end of the passage 9 communicates through a passage 35 with a chamber 11 which communicates through a port 12 with a passage 13 which communicates with a passage 14, the latter opening 35 into the tubing 5 above the unit.

The passage 35 is adapted to be closed by a valve 15. Thus the lower edge of passage 35 constitutes a valve seat against which the valve 15 is constantly urged by a spring 16. To open the valve against the force exerted by the spring 16, a push rod 17 is provided which projects through the passage 35 and is attached at its upper end to the lower end wall of a bellows 18, the upper end of which is anchored to and seals 45 with the upper end wall of chamber 11. The interior of the bellows 18 communicates through a nozzle 19 with a passage 20 which interconnects a chamber 21 and a chamber 22. Chamber 21 communicates through a port 23 with the 50 exterior of the unit 1, and chamber 22 communicates through a port 24 with the passage 14 which is in direct communication with the tubing 5. It will be observed, therefore, that the exterior of the bellows 18 is exposed to the pressure of the 55 fluid in the chamber 11 and the interior of the bellows 18 is exposed to the pressure existent in the passage 20. The upper end of the passage 20 is normally closed by a standing valve 25 and the passage 24 is adapted to be closed by a valve 26 which is urged against a seat at the lower end of the passage 24 by a spring 27. To open the valve 26 a push rod 28 is provided, extending down through the passage 24 and secured thereabove to the end walls 29 and 30, respectively, of a pair of 60 bellows 31 and 32, respectively. The opposite ends of the bellows 31 and 32 are anchored to a rigid tubular member 33 which is anchored to the body member 1 and forms with the bellows 31 and 32 a closed chamber which may be evacuated 65 or may contain some gas at relatively low pressure.

The unit described functions as follows: Assume that the casing 4 contains liquid, the surface of which is only a relatively slight distance 70 below the unit 1 and contains gas above the liquid

at sufficient pressure to support a column of liquid within the tubing 5, which column extends a substantial distance above the unit 1. Under these conditions the exterior of the bellows 18 is exposed to gas in the chamber 11 which is in communication through port 12 and passages 13 and 14 with the tubing 5, which is at relatively low pressure. At the same time the interior of the bellows 18 is exposed through the passages 19 and 20, the chamber 21 and the port 23, to the gas pressure within the casing which is considerably greater than the pressure within the tubing 5. This gas pressure expands the bellows 18 to force the push rod 17 down and open the valve 15, as shown in Fig. 1. At the same time 15 the two bellows 31 and 32, respectively, are exposed to the relatively low gas pressure existing within the tube 5, which pressure acting upon the end wall 30 is insufficient to overcome the force exerted by spring 27 so that the latter holds the 20 valve 26 against its seat. It should be noted at this point that by virtue of the difference in area between the end walls 29 and 30 of the two interconnecting bellows 31 and 32, respectively, the force on the push rod 28 resulting from fluid 25 pressure within the passage 14 is always downward and is proportional to the fluid pressure existing in passage 14.

Under the conditions outlined, the gas pressure in the casing, acting against the surface of the 30 liquid in the casing, forces liquid from the casing up through the tubing 7, past the check valve 10, through the passage 9 and the passage 35 into the chamber 11, thence through port 12 and passages 13 and 14 into the tubing 5. As the 35 liquid rises in the tubing 5, it creates a pressure head within the passages of unit 1 through which it flows, which pressure head is proportional to the height of the column of liquid in tubing 5. This pressure is applied to the exterior 40 of the bellows 31 and 32 and the exterior of bellows 18. In the case of bellows 18, the pressure is opposed by the gas pressure existent in the casing and in the case of the bellows 31 and 32 by the gas pressure in the casing acting upon 45 the under side of valve 26, and by the spring 27. At first the ratio of the fluid pressure in passage 14 to the fluid pressure in the casing is a very small fraction, but as the column of liquid rises in the tubing 5 and the pressure in passage 14 50 approaches the gas pressure in the casing, the aforementioned ratio increases and approaches unity. However, when this ratio reaches a predetermined value less than unity (which predetermined ratio is substantially equal to the ratio 55 of the area of valve passage 24 to the sum of the valve passage area plus the difference between the areas of the bellows end walls 29 and 30), the push rod 28 is moved downward, forcing the valve 26 off its seat and permitting gas to rush 60 from the casing through port 23, passages 21 and 20, past the check valve 25, through passage 22 and passage 24 into passage 14, and thence into the tubing 5. The inflow of gas into the chamber 14 suddenly raises the pressure on the exterior 65 of the bellows 18, compressing the latter and lifting the push rod 17 to permit the spring 16 to close the valve 15. Since the pressure head of the column of liquid in tubing 5 is less than the pressure existing in the casing, gas continues 70 to flow rapidly into the tubing 5 past the valve 26, carrying the column of liquid in the tubing 5 above the unit up through the tubing to the surface and discharging it through the pipe 6.

Since the fluid pressure within the passages 11 75

and 14 is a function of the height of the column of liquid within the tubing 5 regardless of the vertical position of that column, pressure is maintained on the exterior of the bellows 18 and 5 on the bellows 31 and 32, holding the valve 15 closed and the valve 26 open until the column of liquid is discharged from the tubing 5. Immediately following the discharge of the column of liquid through the pipe 6, however, the gas 10 back of the column of liquid which lifted it escapes rapidly through the pipe 6, permitting the gas pressure in the passages 11 and 14 to drop, whereupon the bellows 32 expands and bellows 31 contracts to lift push rod 28 and permit the spring 27 to close valve 26. The closing of valve 26 stops the flow of gas through the passage 20, thereby immediately increasing the pressure in chamber 21 and within the bellows 18, which expands the latter to force the push 15 rod 17 down and open the valve 15. This completes a cycle of operation and a new cycle begins, the operation continuing indefinitely.

It is essential, in order that the valve 15 remain closed until a column of liquid being raised is 20 discharged from the tubing 5, that the pressure in the passage 11 remain as great as the pressure within the bellows 18. The pressure within the passage 11 is substantially the same as that within the tubing 5. However, the pressure within 25 the casing and within passage 21 may be appreciably greater than the pressure within the tubing 5 during the lifting operation because of the pressure drop between passage 23 and passage 14 resulting from friction. It is for this reason that the interior of the bellows 18 is connected by the nozzle 19 with a point in the constricted passage 20. Thus, because of the fact 30 that the space in passage 20 surrounding the nozzle 19 is restricted, the gas rushes through this passage at very high velocity and, as a result of the well-known Venturi effect, has a reduced pressure because of its velocity. It is this reduced pressure which is applied through nozzle 19 to the interior of bellows 18, thereby insuring 35 that the valve 15 will remain closed until the column of liquid being lifted in the tubing 5 is discharged through the pipe 6 and valve 26 closes.

The area of the bellows 18 is preferably made 40 large as compared to the effective area of the valve 15 so that the well pressure acting through the liquid in the passage 9 has little effect in determining the operation of valve 15. In other words, it is desired that the opening and closing 45 of the valve 15 be substantially under the sole control of the bellows 18 which is actuated by the differential of the fluid pressures existent in the passage 11 and the passage 20, respectively.

On the other hand, it is preferred that the 50 fluid pressure acting upon the opposite sides of the valve 26 play an important part in the opening and closing of that valve. Thus, it is desired that the valve 26 open and close in response to the creation of a predetermined ratio 55 between the pressure existing in passage 14 (which is in communication with the tubing 5) and in passage 22 (which is in communication with the gas pressure in the casing) instead of being responsive to the absolute pressure in the passage 14. To this end, the difference between the areas of the bellows end walls 29 and 30, respectively, is preferably made of the same order of magnitude as the effective pressure area of the valve 26. Under these conditions, the gas pressure 60 in the casing acting upon the inner side of

the valve 26 maintains that valve in closed position until the ratio of the pressure resulting from the head of liquid growing in the tubing 5 to the gas pressure in the casing reaches a predetermined value. As a result, if the gas pressure 5 within the casing is maintained at relatively low value, the valve 26 will open and the valve 15 will close when a relatively short column of liquid is accumulated in the tubing 5 and the low gas pressure will suffice to lift this short column of 10 liquid up out of the well. On the other hand, if a higher gas pressure is maintained in the casing, then the column of liquid within the tubing 5 will grow to a greater height before the valve 26 opens and the valve 15 closes to lift the column 15 of liquid out of the well. It will be apparent therefore that the pumping unit is self-compensating for variations in the operating gas pressure available in the casing.

It is to be understood, however, that the unit 20 may be adapted for pumping columns of liquid of fixed height, independent of the gas pressure in the casing, by making the differential of the areas of the bellows ends 29 and 30 large as compared to the pressure area of the valve 26. 25 Obviously, by making this differential area of the bellows sufficiently large as compared to the pressure area of the valve 26, the gas pressure in the casing acting upon the lower side of valve 26 can be made to have very little controlling 30 effect on the movement of the valve. Under these conditions, the stiffness of the spring 27 is increased to provide the chief force opposing the force applied by the bellows to the push rod 28. By varying the force exerted by the spring 35 27, the valve 26 can be made to open in response to the pressure head of a column of liquid of predetermined height in the tubing 5 thereabove, substantially irrespective of the gas pressure existent in the casing. In the preferred arrangement, in which the pressure area of the valve 26 is comparable in magnitude with the differential of the bellows ends 29 and 30, the spring 27 is made relatively weak so that it is not a factor in determining the opening and 40 closing of the valve 27 but merely serves to support the weight of the valve so that the latter will follow the push rod 28 when the latter lifts. 45

The cycle of operations previously described will be repeated regularly as long as there is sufficient liquid pressure in the tubing 1 immediately 50 below the unit 1 to build up a fluid head above the unit sufficient to trip the valves 15 and 26. The pressure of the liquid in the tubing 7 adjacent the unit depends upon the gas pressure 55 within the casing and the liquid level of the casing. Obviously, if the liquid level drops too far below the unit 1, then so much of the liquid head equivalent to the gas pressure within the casing will be employed in lifting the liquid within the tubing 7 up to the unit 1 that there will be insufficient head within the tubing 5 to actuate the valves. However, until this point is reached, as the liquid supply diminishes and the liquid flows more slowly through the unit 1, the gas valve 26 60 remains closed for longer periods of time until the fluid level builds up to a height in the tubing 5 sufficient to trip the valves. Thus there is no loss of gas and no decrease in efficiency as there 65 is in other methods of gas-lift in which gas continues to discharge through the tubing regardless of a decrease in the amount of liquid available.

As an example of the approximate magnitude of the columns of oil that may be lifted with a 70 75

- pump as described, if it is assumed that the effective area of the gas valve 26 subjected to the gas pressure in the casing is 80% of the sum of the differential area of the bellows 31 and 32 and 5 the area of the valve 26 subjected to liquid pressure, then with a gas pressure of 100 pounds per square inch, a liquid pressure in excess of 80 pounds per square inch would be required to open the valve 26. By converting the pounds per 10 square inch unit pressure into feet of head, it will be seen that an operating gas pressure of 100 pounds per square inch will lift a liquid column of approximately 200 feet in height. This allows 15 20% of the total gas pressure for overcoming friction of the column of liquid as it moves up the tubing. In the same manner it may be determined that a gas pressure of 200 pounds per square inch will lift a 400 foot column of liquid to the surface on each cycle.
- 20 Although in most installations it will be found advisable to employ the valve 15 for preventing flow of fluids between the tubing 7 and the passage 14 while the valve 26 is open, this valve 15 and its actuating bellows 18 may be dispensed 25 with under certain conditions of pressure within the tubing 7 relative to the gas pressure in the casing. Thus if the pressure of the liquid within the tubing 7 is relatively low as compared to the gas pressure within the casing, then when the 30 gas valve 26 opens the increase in the pressure within the passage 14, as a result of the free passage of gas from the casing past the valve 26, may be sufficient to prevent further flow of liquid up past the check valve 10 and actually tend to 35 reverse the flow of liquid past the check valve 10, causing the latter to seat. This latter condition would usually result in an installation in which the normal liquid level in the well was below the unit 1 and the pressure within the 40 tubing 7 adjacent the unit is produced solely by the gas pressure within the casing acting upon the surface of the liquid in the casing surrounding the tubing 7. However, in many instances the liquid pressure within the tubing 7 may be even 45 greater than the gas pressure within the casing, under which condition, if the valve 15 were not provided, liquid would continue to flow into the passage 14 while gas was being discharged therethrough past valve 26, causing emulsification if 50 oil containing water is being produced and also producing in the space below the rising column of oil in the tubing 5 a mixture of gas and liquid which greatly reduces the effective pressure acting upon the lower end of the main body 55 of liquid being raised. A particular instance in which the liquid pressure within the tubing 7 may be greater than the gas pressure employed to actuate the unit will be discussed later with reference to Fig. 5.
- 60 As may be gathered from previous description, it is desirable in an installation of the type disclosed in Fig. 1 that the unit 1 be positioned closely adjacent the liquid level in the casing in order that an excessive amount of the total gas pressure available will not be absorbed in lifting the liquid up to the unit through the tubing 7. On the other hand, it is imperative that the gas inlet port 23 be positioned above the level of liquid in the casing else the device cannot 65 function in the manner described, as only liquid would be admitted to the unit through the port 23. However, many wells have a relatively high liquid level when they are first placed on the pump, which level drops by substantial amounts 70 75 as liquid is pumped from the well. Under such

conditions, if the single unit 1, as shown in Fig. 1, were initially installed at such a point in the tubing as to bring the port 23 only a slight distance above the liquid level in the casing, then after the pump had been in operation for a period 5 the liquid level might drop so far below the port 23 as to render the pump inoperative.

To avoid the foregoing difficulty, two or more pumping units may be installed in tandem in the tubing, the upper unit being above the initial 10 level of the liquid in the casing and the lowest unit being adjacent but above the lowest level the liquid in the casing may drop to. Such an installation employing two units 1 and 2, respectively, is shown in Fig. 3. The upper unit 2 need not have 15 a liquid inlet valve but only a gas inlet valve and its construction may be as shown schematically in Fig. 2, in which elements corresponding to those in Fig. 1 bear the same reference numerals with the suffix "a". No separate detailed description of Fig. 2 is necessary.

In Fig. 3, assume that the level A is the initial level of liquid in the casing and that the upper unit 2 is positioned thereabove. Under these conditions the gas pressure in the casing acting 25 against the liquid surface forces liquid up through the tubing 7, through unit 1, through that portion of the tubing 4 between units 1 and 2, and through unit 2 into the tubing 5 thereabove, until the pressure head at unit 2 approaches by a predetermined amount the gas pressure within the casing, whereupon the gas valve 26a (Fig. 2) opens to admit gas through port 24a and carry the column of liquid in tubing 5 above the unit out of the well.

30 Unit 2 continues to operate and unit 1 remains inactive until the liquid in the casing drops to level B which is below the port 24 in unit 1. It is to be understood, of course, that the spacing between units 1 and 2 is less than the difference 40 between the head of liquid produced in tubing 5 by the casing pressure, and the head required in tubing 5 at unit 2 to trip the gas valve in that unit.

When the liquid in the casing reaches the level 45 B, or some other level below port 24 of unit 1, the latter operates as previously described with reference to Fig. 1 and periodically lifts a column of liquid up through the tubing 5 through unit 2, which may or may not function depending upon 50 whether its gas valve is set to open in response to a smaller or a larger head of liquid than is the gas valve of unit 1.

If desired, a simple needle valve as shown in Fig. 10 may be substituted for the unit 2 in Fig. 3 55 to admit a stream of gas from the casing into the tubing 5 to pump liquid by the ordinary gas-lift process until the level of liquid is brought down below unit 1. The needle valve unit shown in Fig. 10 simply comprises a body member 40 60 adapted to be inserted between two sections of the tubing 5 and defining a passage 41 interconnecting the two tubing sections and a passage 42 communicating with the exterior. Passage 42 also communicates with the tubing 5 through a 65 passage 43 having a valve seat on the upper edge thereof against which a needle valve 44 is forced by a spring 45. When the valve is opened, fluid can pass freely from passage 42 through passage 43, thence up around the needle valve 44 and into 70 the tubing through passages 46. The spring 45 is retained in position by a threaded plug 47. The needle valve is normally maintained in closed position by the spring 45 and the latter is of such tension as to permit the needle valve to open only 75

in response to a casing gas pressure substantially greater than that employed to operate unit 1 (Fig. 3) so that after the casing liquid level drops below unit 1 and the latter becomes operative, 5 the casing gas pressure can be reduced to a value too low to open the needle valve.

The advantages of using staged pumping units instead of one pumping unit and a needle valve are: (1) less gas pressure in the casing is required; (2) much less volume of gas is required; 10 (3) there is much less danger of producing an emulsion when a mixture of oil and water is being pumped.

Under some circumstances it may be desirable 15 to employ a packer about the tubing 7 below the unit 1 to prevent the casing gas pressure from being applied to the producing formation in the well. Such an arrangement is shown in Fig. 4, the packer being shown at 48. Except for the 20 use of this packer 48, the installation in Fig. 4 is exactly the same as that in Fig. 1 which has been described in detail. The arrangement shown in Fig. 4 is particularly desirable in a well which produces a large volume of liquid at little or 25 no pressure. The packer 48 is preferably positioned relatively close to the unit 1 and of course both must be positioned a substantial distance below the normal level of the liquid in the casing so that the liquid pressure below the packer 48 30 will be sufficient to force the liquid up through the unit 1 and into the tubing 5 and produce in the latter a column of liquid to be lifted of substantial height. Gas pressure within the casing 4 above the packer 48 to lift the liquid must then 35 be supplied from some external source through the pipe 8. In order to secure maximum production, the pressure of the gas supplied to the casing should be slightly in excess of the pressure head existing in the liquid below the packer 48.

In the arrangement of Fig. 4 there are two 40 independent passages from the unit 1 to the surface, one through the tubing 5 and the other through the casing 4 surrounding the tube. Therefore, either one of these passages may be 45 used for discharging the liquid and the other employed for supplying the gas pressure. In some instances it may be desirable to supply the gas under pressure through the tubing 5 and deliver the oil through the casing 4. This merely 50 involves a re-design of the unit 1, as shown schematically in Fig. 6, in which elements corresponding to those of Fig. 1 bear the same reference numerals with the suffix "b".

It will be observed that the unit comprises a 55 standing valve 10b the same as in the unit of Fig. 1 and a liquid inlet valve 15b controlled by a spring 16b and a bellows 18b. However, the chamber 11b, in which the bellows 18b is mounted, communicates with the exterior through a 60 port 50 instead of communicating with the tubing 5, as in Fig. 1. The bellows 31b and 32b are inverted and the exteriors of both are in communication with the exterior of the unit through ports 50 and 51. The valve 26b is likewise inverted and the passage 22 communicates with the tubing 5 through a Venturi passage 20b. The interior of the bellows 11b is communicated 65 through a passage 52 and a nozzle 19b with the Venturi passage 20b.

70 By comparing the construction of the unit shown in Fig. 6 with that shown in Fig. 1, it will be observed that gas pressure in the tubing 5 acts upon the bellows 18b to open the valve 15b and permit liquid to flow from the tubing 7 up 75 past the check valve 10b and the valve 15b

through the port 50, into the casing above the packer 48. A column of liquid will rise in the casing until its head is sufficient to actuate the bellows 31b and the bellows 18b to open the valve 26b and close the valve 15b, whereupon gas will be discharged from the tubing 5 down past the valve 26b and out through port 51 into the casing to lift the column of liquid in the casing. 5

One advantage of employing the arrangement shown in Fig. 6 instead of that shown in Fig. 4 10 is that the unit 1 and the packer 48 may be initially installed at any desired depth of oil in the casing 4 since gas can always be supplied to the unit through the tubing 5 regardless of the height of the liquid surrounding the tubing. 15

Still another system in which my unit may be employed is illustrated in Fig. 5, in which the unit 1 corresponding to the unit shown in Fig. 1 is inserted in a string of tubing 55, which in turn is positioned within an outer tubing 56 mounted 20 within the well casing 4. A seat 57 is provided in the tubing 56 which supports the unit 1 and seals with the latter. Tubing 58 may be extended below the seating member 57 to serve as a gas anchor. The tubing 59 below the unit 1 extends 25 into the liquid to be pumped. The tubing 55 is open at the upper end for the discharge of liquid and gas but the tubing 56 and the casing 4 are sealed off at the top and gas from casing 4 is supplied through a reducing valve 60 to the 30 tubing 56 to actuate the unit 1.

The system of Fig. 5 is particularly adapted for 35 oil wells in which the oil production is small and the gas pressure is large and it is necessary to apply a reduced gas pressure to the unit 1 in order to limit the pumping capacity to the producing capacity of the well. By choosing a pressure reducing valve 60 of the proper characteristics, any desired gas pressure may be supplied to the tubing 56 to cause the unit 1 to pump at a 40 low capacity.

It should be noted that in an installation of 45 the type disclosed in Fig. 5 it is absolutely necessary that the unit 1 have a liquid inlet valve 15 (Fig. 1) since the pressure of the liquid supplied to the unit may be much greater than the gas pressure employed to lift the liquid. Therefore if, when valve 26 opened, the valve 15 did not close, large quantities of liquid would still enter the tubing above the unit and would be 50 mixed with the gas, causing the entire system to operate as a conventional gas-lift system.

Obviously a unit of the type disclosed in Fig. 5 may be employed in a system as shown in Fig. 5 and the gas pressure supplied to the tubing 55 and the oil exhausted through the tubing 56. It 55 is also understood that gas to operate the unit may be supplied from a separate source instead of from the casing 4.

Units of the type disclosed in the schematic 60 diagrams of Figs. 1 and 2 may be constructed in actual practice as shown in Figs. 7, 8 and 9, respectively. Thus Fig. 7 shows the upper portion and Fig. 8 shows the lower portion of an actual unit corresponding to the unit 1 in Fig. 1. It will be observed that this unit comprises an 65 upper tubular member 65 adapted to screw onto the lower end of the tubing 5 and threaded at its lower end into a coupling member 66 which couples it to a second tubular member 67 positioned therebelow, the latter in turn being threaded into a coupling member 68 which connects it to a tubular member 69 which at its 70 lower end is threaded onto an adapter 70 which connects to the tubing 7 below the unit. A valve 75

seat 71 is clamped between the members 69 and 70 which cooperates with the standing valve 10. The latter is preferably urged toward its seat by a retainer 72 which is urged downward by a spring 73 seating against a shoulder 74 in the member 69.

The ball valve 15 is also mounted within the member 69 and is urged upward against its seat 75 by the spring 16 which is compressed between 10 the shoulder 74 and a retainer 76 positioned below the ball 15. The push rod 17 for opening the valve 15 has a guide 77 thereon slidably positioned within a passage provided therefor in the member 68 and is joined by a threaded shaft 78 15 to the lower end member 79 of the bellows 18. The bellows 18 is attached at its upper end to a rigid tubular member 80 which is threaded at its upper end into the coupling member 66.

The nozzle 19 is a separate member which is 20 threaded into the upper end of the tubular member 80 and extends into a valve seat 81 which defines the passage 20. The valve seat 81 is clamped in position between the coupling member 66 and a tubular guide member 82 which 25 slidably supports a retainer 83 for the check valve 25 which seats against seat 81. The coupling member 66 has longitudinal passages 84 extending therethrough which correspond to the passage 13 in Fig. 1 and it also has lateral passages 85 therein extending to the exterior, which 30 correspond to the gas inlet passage 23 in Fig. 1.

The tubular member 82 supports a tubular member 86 to which it is joined by screw threads and the tubular member 86 is connected also by 35 screw threads to the bellows anchor member 87 which supports the bellows 31 and 32, respectively. The end wall 30 of the bellows 32 is constituted by a conical member into which the upper end of the shaft 28 is threaded. Likewise 40 the end wall 29 of the lower bellows 31 is relatively thick or elongated and screws onto the lower end of the shaft 28 and onto the upper end of a shaft 28' which constitutes the push rod for opening the ball valve 26. A guide 88 is 45 mounted upon the rod 28, the ball 26 seats against a seat 89 clamped between the members 82 and 86, respectively, and the ball is normally urged against its seat by the spring 27, through a retainer 90.

50 The various passages through the units shown in Figs. 7 and 8 may be traced from bottom to top as follows: The tubing 7 communicates through the hollow member 70 and the seat 71 past the check valve 10 with the passage 9 within the hollow member 69, thence past valve 15 when 55 the latter is open, through the seat 75, past the guide 77 into the passage 11 surrounding the bellows 18, from thence through the passages 84 into the space defined between the outer tubular member 65 and the members 82 and 86, and the bellows supporting element 87, to the tubing 5. Gas entering through the ports 23 goes through 60 the passages 85, through the valve seat 20, thence up past the guide 83, past the valve 26, through the seat 89, past the guide 88, at which point it 65 communicates with the space between the tubular member 86 and the outer casing member 65 through ports 91.

The unit shown in Fig. 9 corresponds exactly 70 with the upper portion of the unit I shown in Fig. 7 and corresponding parts bear the same reference numerals with the suffix "a" added thereto. The only difference is that instead of the member 80, the member 67 and the parts 75 positioned therebelow being employed, the tub-

ing 5a connected to the lower end of the unit is joined directly through an adapter 92 to the lower end of the coupling member 66a.

Although the invention has been described with reference to several specific systems and by disclosing in detail one possible method of construction, it is to be understood that changes may be made in the system and in the particular constructions disclosed without departing from the invention and the latter is to be limited only as set forth in the appended claims.

I claim:

1. In a gas-lift pumping system for a well having a casing containing liquid to be pumped in the lower portion thereof and gas under pressure 15 in the casing above the liquid surface therein; a string of tubing within the casing having its upper end extending out of the casing and its lower end submerged in the liquid in the casing, gas valve means for admitting gas from said casing into said tubing at a first level, liquid valve means for controlling flow of fluid through said tubing from a level below said first level, and means for closing said gas valve and opening said liquid valve when the pressure in the tubing falls below a predetermined value and for opening said gas valve and closing said liquid valve when the fluid pressure in the tubing at said first level reaches a predetermined ratio with respect to the gas pressure in said casing, whereby a column of liquid rises in said tubing when said liquid valve is open until the pressure head of said column reaches said predetermined ratio with respect to the gas pressure in said casing and said column of liquid is then lifted up through said tubing by gas admitted therebelow through said gas valve. 30

2. In a gas-lift pumping system for a well having a casing containing liquid to be pumped in the lower portion thereof, the surface of said liquid varying between a lower level and an upper level and gas under pressure in the casing above the liquid surface therein, the gas pressure being sufficient to support a column of said liquid of a height less than the depth of said well to said liquid surface; an open ended string of tubing within the casing having its upper end extending out of the casing and its lower end submerged in said liquid at a point below said lower level, first valve means for communicating said tubing with the casing at a first level above said upper level in response to increase of fluid pressure within said tubing at said first level above a predetermined value less than the gas pressure in the casing, second valve means for communicating said tubing with the casing at a second level below said first level but above said lower level of liquid in the casing, in response to increase of fluid pressure within said tubing at said second level above a predetermined value less than the fluid pressure in the casing at said second level, 40 said first valve means closing at tubing pressures at said first level below a predetermined value less than said first mentioned predetermined value, and said second valve means closing at tubing pressures at said second level below a predetermined value less than said second mentioned predetermined value, and the distance between said first and second valves being less than the height of a liquid column having a pressure head 45 equal to the difference between the gas pressure in the casing and said first-mentioned predetermined pressure.

3. In a gas-lift pumping system for a well having a casing containing liquid to be pumped in the lower portion thereof, the surface of said 50

70

75

liquid varying between a lower level and an upper level, and gas under pressure in the casing above the liquid surface therein, a string of tubing within the casing having its upper end extending out of the casing and its lower end submerged in said liquid at a point below said lower level, first valve means for communicating said tubing with the casing at a first level adjacent said upper level in response to an increase of the ratio of the fluid pressure within said tubing at said first level to the fluid pressure in the casing at said first level to a predetermined value less than unity, second valve means for communicating said tubing with the casing at a second level below said first level but adjacent said lower level of liquid in the casing in response to an increase of the ratio of the fluid pressure within said tubing at said second level to the fluid pressure in the casing at said second level to a predetermined value less than unity, said first valve means closing in response to a decrease in the tubing pressure at said first level below a predetermined value and said second valve means closing in response to a decrease in the tubing pressure at said second level below a predetermined value.

4. In a gas-lift pumping system for a well having a casing containing liquid to be pumped in the lower portion thereof, the surface of said liquid varying between a lower level and an upper level, and gas under pressure in the casing above the liquid surface therein; an open ended string of tubing within the casing having its upper end extending out of the casing and its lower end submerged in said liquid at a point below said lower level, first valve means for communicating said tubing with the casing at a first level above said upper level in response to increase of fluid pressure within said tubing at said first level above a predetermined value less than the gas pressure in the casing, second valve means for communicating said tubing with the casing at a second level below said first level but above said lower level of liquid in the casing in response to increase of fluid pressure within said tubing at said second level above a predetermined value less than the fluid pressure in the casing at said second level, said first valve means closing at tubing pressures at said first level below a predetermined value less than said first mentioned predetermined value and said second valve means closing at tubing pressures at said second level below a predetermined value less than said second mentioned predetermined value, the distance between said first and second valves being less than the height of a liquid column having a pressure head equal to the difference between the gas pressure in the casing and said first-mentioned predetermined pressure, and third valve means for closing said tubing at a level adjacent and below said second level in response to increase of fluid pressure within said tubing at said second level to a value above said second mentioned predetermined value.

5. A gas-lift pumping system for a well having a casing containing liquid to be pumped in the lower portion thereof, the surface of said liquid varying between a lower level and an upper level, and gas under pressure in the casing above the liquid surface therein, a string of tubing within the casing having its upper end extending out of the casing and its lower end submerged in said liquid at a point below said lower level, first valve means for communicating said tubing with the casing at a first level adjacent the said upper level in response to an increase in the ratio of the fluid pressure within said tubing at said first level

to the fluid pressure in the casing at said first level above a predetermined value less than unity, second valve means for communicating said tubing with the casing at a second level below said first level and adjacent said lower level of liquid in the casing in response to an increase in the ratio of the fluid pressure within said tubing at the second level to the fluid pressure in the casing at said second level above a predetermined value less than unity, said first valve means closing in response to reduction of tubing pressure at said first level below a first predetermined value, and said second valve means closing in response to reduction of tubing pressure at said second level below a second predetermined value, and third valve means for closing said tubing at a level adjacent and below said second level in response to an increase of said second ratio above said second predetermined value, said third valve means opening in response to a reduction in said second ratio below said second predetermined value.

6. In a gas-lift pumping system for a well having a casing containing liquid to be pumped in the lower portion thereof and gas at relatively high pressure thereabove; a first string of tubing within the casing and extending into the liquid therein, and a second string of tubing within said first tubing, the first tubing being closed at the top and the second tubing open at the top, means sealing said first tubing about said second tubing adjacent the liquid within said well, means for admitting gas at reduced pressure from said casing into said first tubing at a point above said sealing means, a first valve means for admitting gas from said first tubing into said second tubing adjacent and above said sealing means, second valve means for controlling the flow of fluid through said second tubing at a point below the point of admission of gas thereinto, and means for opening said first valve means and closing said second valve means in response to fluid pressure within said second tubing of predetermined magnitude relative to and less than the fluid pressure within said first tubing and closing said first valve means and opening said second valve means in response to decrease in the fluid pressure within said second tubing below a predetermined value less than said first predetermined value whereby a column of liquid rises in said second tubing through said second valve until the pressure head of said column reaches said first predetermined value, whereupon said column of liquid is lifted up through said tubing by gas admitted therebelow from said first tubing through said first valve.

7. In a gas-lift pumping system for a well having a casing containing liquid to be pumped in the lower portion thereof and gas at relatively high pressure thereabove; a first string of tubing within the casing and extending into the liquid therein and a second string of tubing within said first tubing, means sealing said first tubing about said second tubing adjacent the liquid level within said well, means for admitting gas at reduced pressure from said casing into said first tubing at a point above said sealing means, a gas valve means for admitting gas from said first tubing into said second tubing adjacent and above said sealing means, liquid valve means for controlling flow of liquid from said casing below said gas valve means through said second tubing, and means responsive to the pressure in said second and first tubings, respectively, for opening said gas valve and closing said liquid valve when

- the ratio of the pressure in the second tubing to the pressure in the first tubing exceeds a predetermined value less than unity and for closing said gas valve means and opening said liquid valve means when the pressure in the second tubing falls below a predetermined value whereby a column of liquid from the casing rises through said liquid valve into said second tubing until said ratio reaches said predetermined value whereupon said column of liquid is lifted up through said second tubing by gas admitted therebelow from said first tubing through said gas valve.
8. In a gas-lift pumping system for a well having a casing containing liquid to be pumped in the lower portion thereof, a string of tubing within the casing having its lower end submerged in the liquid therein, means for supplying gas under pressure to said tubing at the surface, valve means for supplying gas from said tubing into the casing at a point below the normal liquid level therein, said valve seeking its closed position in the absence of fluid pressure in said tubing and casing, and means responsive to fluid pressure existing in said casing for opening said valve means when the pressure in the casing rises to a predetermined value less than the gas pressure in said tubing and closing said valve means when the pressure in the casing falls below a value less than said predetermined value, said valve remaining open in response to all casing pressures exceeding said predetermined value.
9. In a gas-lift pumping system for a well having a casing containing liquid to be pumped in the lower portion thereof, a string of tubing within the casing having its lower end submerged in the liquid therein, means for supplying gas under pressure to said tubing at the surface, valve means for admitting gas from said tubing into the casing at a point below the normal liquid level therein, and means responsive to fluid pressures existent in the casing and in said tubing, respectively, for opening said valve means when the ratio of the pressure in the casing to the pressure in the tubing reaches a predetermined value less than unity and closing said valve means when the pressure in the casing falls below a predetermined value.
10. In a gas-lift pumping system for a well having a casing containing liquid to be pumped in the lower portion thereof, a string of tubing within said casing having its upper end extending out of said casing, and its lower end submerged in said liquid, means sealing between said tubing and the casing at a point adjacent the normal liquid level therein, means for supplying gas under pressure to said tubing at the surface, gas valve means for discharging gas from said tubing into said casing at a point adjacent to and above said sealing means, liquid valve means for controlling flow of liquid from the casing below the sealing means to the casing above the sealing means, and means for opening said gas valve means and closing said liquid valve means in response to fluid pressure in said casing at a level adjacent said sealing means greater than a predetermined pressure, which predetermined pressure is less than the gas pressure in said tubing, and closing said gas valve and opening said liquid valve in response to decrease of the pressure in said casing below a predetermined value less than said first mentioned predetermined value whereby a column of liquid rises in the casing above said sealing means through said liquid valve until the pressure head of said column reaches said first predetermined value whereupon said column of liquid is lifted up through the casing by gas admitted therebelow from said tubing through said first valve.
11. In a gas-lift pumping system for a well having a casing containing liquid to be pumped in the lower portion thereof, a string of tubing within said casing having its upper end extending out of said casing and its lower end submerged in said liquid, means sealing between said tubing and the casing at a point adjacent the normal liquid level therein, means for supplying gas under pressure to said tubing at the surface, gas valve means for discharging gas from said tubing into said casing at a point adjacent to and above said sealing means, liquid valve means for controlling flow of fluid from the casing below the sealing means to the casing above the sealing means, means for opening said liquid valve means and closing said gas valve means in response to a decrease in the pressure in said casing below a predetermined value, and means for opening said gas valve means and closing said liquid valve means in response to increase of the ratio of the fluid pressure in said casing above said sealing means to the gas pressure in said tubing above a predetermined value less than unity, whereby a column of liquid rises in the casing above said sealing means through said liquid valve until said predetermined ratio is exceeded whereupon said column of liquid is lifted up through the casing from gas admitted therebelow from said tubing through said gas valve.
12. A gas-lift pumping unit adapted for insertion in a well and defining a first passage for the entry of well fluid, a second passage for the discharge of well fluid to the surface, and a third passage for supplying gas under pressure to said second passage, gas valve means interconnecting said second and third passages for admitting gas under pressure to discharge a column of liquid upwardly through said second passage, liquid valve means interconnecting said first and second passages for passing well fluid from said first passage to said second passage, first means for intermittently opening said gas valve to admit gas from said third passage to said second passage to elevate a column of liquid in said second passage up therethrough and out of the well, and closing said gas valve to permit a new column of liquid to form in said second passage, and second means mechanically independent of said first means for opening said liquid valve in response to closure of said gas valve and closing said liquid valve in response to opening of said gas valve.
13. A gas-lift pumping unit adapted for insertion in a well and defining a first passage for the entry of well fluid, a second passage for the discharge of well fluid to the surface, and a third passage for supplying gas under pressure to said second passage, gas valve means interconnecting said second and third passages for admitting gas under pressure to discharge a column of liquid upwardly through said second passage, liquid valve means interconnecting said first and second passages for passing well fluid from said first passage to said second passage, means responsive to fluid pressure existing in said second passage for opening said gas valve when the pressure in the second passage exceeds a predetermined value and closing said gas valve when the pressure in the second passage falls below a predetermined value less than said first predetermined value, and second means for opening said liquid valve

in response to closure of said gas valve and closing said liquid valve in response to opening of said gas valve.

14. A gas-lift pumping unit as described in claim 13 in which said gas valve comprises means defining a port between said third and second passages and a closure member movable toward said port in the direction of fluid flow from said third to said second passage whereby frictional resistance of said closure member to said fluid flow tends to close said valve.

15. A gas-lift pumping unit adapted for insertion in a well and defining a first passage for the entry of well fluid, a second passage for the discharge of well fluid to the surface, and a third passage for supplying gas under pressure to said second passage, gas valve means interconnecting said second and third passages for admitting gas under pressure to discharge a column of liquid upwardly through said second passage, liquid valve means interconnecting said first and second passages for passing said fluid from said first passage to said second passage, first means responsive to fluid pressure existent in said second and third passages, respectively, for opening said gas valve when the ratio of the pressure in the second passage to the pressure in the third passage exceeds a predetermined value less than unity and closing said gas valve when the pressure in the second passage falls below a predetermined value, and second means for opening said liquid valve in response to closure of said gas valve and closing said liquid valve in response to opening of said gas valve.

35 16. A gas-lift pumping unit adapted for insertion in a well and defining a first passage for the entry of well fluid, a second passage for the discharge of well fluid to the surface, and a third passage for supplying gas under pressure to said second passage, gas valve means interconnecting said second and third passages for admitting gas under pressure to discharge a column of liquid upwardly through said second passage, liquid valve means interconnecting said first and second passages for passing well fluid from said first passage to said second passage, first means responsive to fluid pressures existent in said second and third passages, respectively, for opening said gas valve when the ratio of the pressure in the second passage to the pressure in the third passage exceeds a predetermined value less than unity and closing said first valve when the pressure in the second passage falls below a predetermined value, said gas valve comprising means defining a port between said third and second passages and a closure member movable toward said port in the direction of fluid flow therethrough from said third to said second passage whereby frictional resistance of said closure member to said fluid flow tends to close said gas valve, and second means for opening said liquid valve in response to closure of said gas valve and closing said liquid valve in response to opening of said gas valve.

65 17. A gas-lift pumping unit adapted for insertion in a well and defining a first passage for the entry of well fluid, a second passage for the discharge of well fluid to the surface, and a third passage for supplying gas under pressure to said second passage, gas valve means interconnecting said second and third passages for admitting gas under pressure to discharge a column of liquid upwardly through said second passage, liquid valve means interconnecting said first and second passages for passing well fluid from said first pas-

sage to said second passage, first means responsive to fluid pressures existent in said second and third passages, respectively, for opening said gas valve when the ratio of the pressure in the second passage to the pressure in the third passage exceeds a predetermined value less than unity, and closing said gas valve when the pressure in the second passage falls below a predetermined value, said first pressure responsive means including means responsive at all times to pressure in said second passage for tending to open the gas valve in response to such pressure, and means responsive to pressure in said third passage only when said gas valve is closed tending to close said gas valve in response to third passage pressure whereby closing force on said gas valve increases as the valve moves from open to closed position, and second means for opening said liquid valve in response to closure of said gas valve and closing said liquid valve in response to opening of said gas valve.

18. A gas-lift pumping unit adapted for insertion in a well and defining a first passage for the entry of well fluid, a second passage for the discharge of well fluid to the surface, and a third passage for supplying gas under pressure to said second passage, gas valve means interconnecting said second and third passages for admitting gas under pressure to discharge a column of liquid upwardly through said second passage, liquid valve means interconnecting said first and second passages for passing well fluid from said first passage to said second passage, first means for intermittently opening said gas valve to admit gas from said third passage to said second passage to elevate a column of liquid in said second passage up therethrough and out of the well and closing the gas valve to permit a new column of liquid to form in said second passage, and second means for opening said liquid valve in response to closure of said gas valve and closing said liquid valve in response to opening of said gas valve, in which said gas valve and means for opening and closing it comprise a port between said third and second passages, a closure member movable toward and away from said port on the third passage side thereof, auxiliary means responsive to pressure in said second passage for urging said closure member into open position, and yieldable means for urging said closure member into closed position.

19. A gas-lift pumping unit adapted for insertion in a well and defining a first passage for the entry of well fluid, a second passage for the discharge of well fluid to the surface, and a third passage for supplying gas under pressure to said second passage, gas valve means interconnecting said second and third passages for admitting gas under pressure to discharge a column of liquid upwardly through said second passage, liquid valve means interconnecting said first and second passages for passing well fluid from said first passage to said second passage, first means for intermittently opening said valve to admit gas from said third passage to said second passage to elevate a column of liquid in said second passage up therethrough and out of the well, and closing said gas valve to permit a new column of liquid to form in said second passage, second means for opening said liquid valve in response to closure of said gas valve and closing said liquid valve in response to opening of said gas valve, in which said gas valve and means for opening and closing it comprise a valve seat defining a port interconnecting said third and second passages, a valve

- movable toward and away from said seat whereby said valve when seated exposes effective pressure areas to fluids in said third and second passages, respectively, the pressure in said third passage tending to urge said valve against its seat, and additional means comprising a pair of members each having an outer face responsive to fluid pressure in said second passage for applying an opening force to said valve which is proportional to the fluid pressure in the second passage, one of said members exposing a face of a larger effective pressure area than the other and tending to move in such direction as to open said valve.
20. A gas-lift pumping unit adapted for insertion in a well and defining a first passage for the entry of well fluid, a second passage for the discharge of well fluid to the surface, and a third passage for supplying gas under pressure to said second passage, gas valve means interconnecting said second and third passages for admitting gas under pressure to discharge a column of liquid upwardly through said second passage, liquid valve means interconnecting said first and second passages for passing well fluid from said first passage to said second passage, first means for intermittently opening said gas valve to admit gas from said third passage to said second passage to elevate a column of liquid in said second passage up therethrough and out of the well, and closing said gas valve to permit a new column of liquid to form in said second passage, second means for opening said liquid valve in response to closure of said gas valve and closing said liquid valve in response to opening of said gas valve, said gas valve and means for opening and closing it comprising a valve seat defining a port interconnecting said third and second passages, a closure member movable toward and away from said seat whereby said closure member when seated exposes effective pressure areas to fluids in said second and third passages, respectively, pressure in said third passage tending to urge said valve against its seat, and additional means comprising a pair of members each having an outer face responsive to fluid pressure in said second passage for applying an opening force to said valve which is proportional to the fluid pressure in the second passage, one of said members exposing a face of larger effective pressure area than the other and tending to move in such direction as to open said closure member, and means further provided for yieldably resisting the opening force of the said member applied to said valve.
21. A gas-lift pumping unit adapted for insertion in a well and defining a first passage for the entry of well fluid, a second passage for the discharge of well fluid to the surface, and a third passage for supplying gas under pressure to said second passage, gas valve means interconnecting said second and third passages for admitting gas under pressure to discharge a column of liquid upwardly through said second passage, liquid valve means interconnecting said first and second passages for passing well fluid from said first passage to said second passage, first means for intermittently opening said gas valve to admit gas from said third passage to said second passage to elevate a column of liquid in said second passage up therethrough and out of the well, and closing said gas valve to permit a new column of liquid to form in said second passage, and second means mechanically independent of said first means responsive to fluid pressure in said second and third passages, respectively, for opening said liquid valve when the pressure in the third passage exceeds the pressure in the second passage by a predetermined differential and closing the liquid valve in response to a decrease in the said differential pressure below a predetermined value.
22. A gas-lift pumping unit adapted for insertion in a well and defining a first passage for the entry of well fluid, a second passage for the discharge of well fluid to the surface, and a third passage for supplying gas under pressure to said second passage, gas valve means interconnecting said second and third passages for admitting gas under pressure to discharge a column of liquid upwardly through said second passage, liquid valve means interconnecting said first and second passages for passing well fluid from said first passage to said second passage, first means for intermittently opening said gas valve to admit gas from said third passage to said second passage to elevate a column of liquid in said second passage up therethrough and out of the well, and closing said gas valve to permit a new column of liquid to form in said second passage, said liquid valve means comprising a check valve mechanically independent of said first means for permitting fluid flow from said first to said second passage and preventing fluid flow from said second to said first passage.
23. A gas-lift pumping unit adapted for insertion in a well and defining a first passage for the entry of well fluid, a second passage for the discharge of well fluid to the surface, and a third passage for supplying gas under pressure to said second passage, gas valve means interconnecting said second and third passages for admitting gas under pressure to discharge a column of liquid upwardly through said second passage, liquid valve means interconnecting said first and second passages for passing well fluid from said first passage to said second passage, first means for intermittently opening said gas valve to admit gas from said third passage to said second passage to elevate a column of liquid in said second passage up therethrough and out of the well, and closing said gas valve to permit a new column of liquid to form in said second passage, and second means mechanically independent of said first means responsive to fluid pressure in said second and third passages, respectively, for opening said liquid valve when the pressure in the third passage exceeds the pressure in the second passage by a predetermined differential and closing the liquid valve in response to a decrease in the said differential pressure below a predetermined value.
24. A gas-lift pumping unit adapted for insertion in a well and defining a first passage for

the entry of well fluid, a second passage for the discharge of well fluid to the surface, and a third passage for supplying gas under pressure to said second passage, gas valve means interconnecting said second and third passages for admitting gas under pressure to discharge a column of liquid upwardly through said second passage, liquid valve means interconnecting said first and second passages for passing well fluid from said first passage to said second passage, first means for intermittently opening said gas valve to admit gas from said third passage to said second passage to elevate a column of liquid in said second passage up therethrough and out of the well, and closing said gas valve to permit a new column of liquid to form in said second passage, and second means responsive to fluid pressures in said second and third passages, respectively, for opening said liquid valve when the pressure in the third passage exceeds the pressure in the second passage and closing said liquid valve in response to increase of the pressure in the second passage to a value substantially equal to the pressure in the third passage.

25. A gas-lift pumping unit adapted for insertion in a well and defining a first passage for the entry of well fluid, a second passage for the discharge of well fluid to the surface, and a third passage for supplying gas under pressure to said second passage, gas valve means interconnecting said second and third passages for admitting gas under pressure to discharge a column of liquid upwardly through said second passage, liquid valve means interconnecting said first and second passages for passing well fluid from said first passage to said second passage, first means for intermittently opening said gas valve to admit gas from said third passage to said second passage to elevate a column of liquid in said second passage up therethrough and out of the well, and closing said gas valve to permit a new column of liquid to form in said second passage, and second means for actuating said liquid valve comprising a member having a pressure face exposed to pressure in said third passage and tending to open the liquid valve and a pressure face exposed to pressure in said second passage and tending to close said liquid valve whereby said valve opens and closes in response to variations in the differential pressure of said second and third passages.

50. 26. A gas-lift pumping unit as described in claim 25, in which the pressure faces on said second means are of substantially equal areas whereby said second means tends to open said liquid valve in response to increase of the pressure in the third passage above the pressure in the second passage.

27. A gas-lift pumping unit adapted for insertion in a well and defining a first passage for the entry of well fluid, a second passage for the discharge of well fluid to the surface, and a third passage for supplying gas under pressure to said second passage, gas valve means interconnecting said second and third passages for admitting gas under pressure to discharge a column of liquid upwardly through said second passage, liquid valve means interconnecting said first and second passages for passing well fluid from said first passage to said second passage, first means for intermittently opening said gas valve to admit gas from said third passage to said second passage to elevate a column of liquid in said second passage up therethrough and out of the well, and closing said gas valve to permit a new column of liquid to form in said second passage, and second means

responsive to fluid pressure in said second and third passages, respectively, for opening said liquid valve when the pressure in the third passage exceeds the pressure in the second passage by a predetermined differential, and additional means responsive to the opening of said gas valve for varying the last mentioned pressure differential locally about the second pressure responsive means whereby the pressure in the second passage is effective to close the liquid valve when said gas valve is open.

28. A gas-lift pumping unit adapted for insertion in a well and defining a first passage for the entry of well fluid, a second passage for the discharge of well fluid to the surface, and a third passage for supplying gas under pressure to said second passage, gas valve means interconnecting said second and third passages for admitting gas under pressure to discharge a column of liquid upwardly through said second passage, liquid valve means interconnecting said first and second passages for passing well fluid from said first passage to said second passage, first means for intermittently opening said gas valve to admit gas from said third passage to said second passage to elevate a column of liquid in said second passage up therethrough and out of the well, and closing said gas valve to permit a new column of liquid to form in said second passage, second valve control means responsive to fluid pressures existent in said second and third passages, respectively, for opening said liquid valve when the pressure in the third passage at the point therein where it affects said second valve control means exceeds the pressure in the second passage, and closing said liquid valve when the pressure in the second passage is substantially equal to the pressure at said point in the third passage, and means for locally reducing the pressure at said point in said third passage when said first valve is open.

29. A gas-lift pumping unit adapted for insertion in a well and defining a first passage for the entry of well fluid, a second passage for the discharge of well fluid to the surface, and a third passage for supplying gas under pressure to said second passage, gas valve means interconnecting said second and third passages for admitting gas under pressure to discharge a column of liquid upwardly through said second passage, liquid valve means interconnecting said first and second passages for passing well fluid from said first passage to said second passage, first means for intermittently opening said gas valve to admit gas from said third passage to said second passage to elevate a column of liquid in said second passage up therethrough and out of the well, and closing said gas valve to permit a new column of liquid to form in said second passage, second means responsive to fluid pressures existent in said third and second passages, respectively, for opening said liquid valve when the pressure in the third passage where it affects said second valve control means exceeds the pressure in the second passage and closing said liquid valve when the pressure in the second passage exceeds the pressure at the point in the third passage where it affects said second valve control means, and pressure reducing means acting upon the fluid at said point in said third passage for reducing the pressure of the fluid locally at that point when said first valve is open.

30. A gas-lift pumping unit adapted for insertion in a well and defining a first passage for the entry of well fluid, a second passage for the dis-

- charge of well fluid to the surface, and a third passage for supplying gas under pressure to said second passage, gas valve means interconnecting said second and third passages for admitting gas under pressure to discharge a column of liquid upwardly through said second passage, liquid valve means interconnecting said first and second passages for passing well fluid from said first passage to said second passage, first means for intermittently opening said gas valve to admit gas from said third passage to said second passage to elevate a column of liquid in said second passage up therethrough and out of the well, and closing said gas valve to permit a new column of liquid to form in said second passage, second means responsive to fluid pressures existent in said second and third passages, respectively, for opening said liquid valve when the pressure at a predetermined point in the third passage exceeds the pressure in the second passage, and closing said liquid valve when the pressure in the second passage is substantially equal to the pressure at said predetermined point in the third passage, and means including a Venturi constriction for reducing the fluid pressure at said predetermined point when fluid is admitted through the third passage and said gas valve, to reduce the pressure of that fluid locally where it is effective on the second valve control means to a value substantially equal to or below the pressure of the fluid in the second passage where it is effective on said second control means.
31. A gas-lift unit comprising a body member adapted for insertion in a well and defining a first passage for communication with liquid in the well, a second passage for communication with a liquid discharge line extending out of the well and a third passage for communication with a source of gas under pressure, means interconnecting said first and second passages for admitting liquid from the well into said liquid discharge line; means including a valve interconnecting said second and third passages for admitting gas under pressure from said source to the liquid discharge line to lift a column of liquid therein up out of the well, and valve control means therefor; said valve and valve control means comprising a valve seat defining a port interconnecting said second and third passages, a valve movable toward and away from said seat whereby said valve when seated exposes equal effective areas to fluids in said second and third passages, respectively, the pressure in said third passage tending to urge said valve against its seat and the pressure in said second passage tending to open said valve, and additional means responsive to fluid pressure in said second passage for applying an opening force to said valve which is proportional to the fluid pressure in the second passage.
32. A gas-lift pumping unit comprising a body member adapted for insertion in a well and defining a first passage for communication with liquid in the well, a second passage for communication with a liquid discharge line extending out of the well and a third passage for communicating with a source of gas under pressure; means interconnecting said first and second passages for admitting liquid from the well into said liquid discharge line; means including a valve interconnecting said second and third passages for admitting gas under pressure from said source to the liquid discharge line to lift a column of liquid therein up out of the well, and valve control means therefor; said valve and control means

comprising a valve seat defining a port interconnecting said second and third passages, a valve movable against and away from said seat, spring means for applying a force tending to close said valve, and means responsive to fluid pressure in said second passage for applying an opening force to said valve which is proportional to the fluid pressure in the second passage.

33. A gas-lift pumping unit comprising a body member adapted for insertion in a well and defining a first passage for communication with liquid in the well, a second passage for communication with a liquid discharge line extending out of the well and a third passage for communication with a source of gas under pressure; means interconnecting said first and second passages for admitting liquid from the well into said liquid discharge line; means including a valve interconnecting said second and third passages for admitting gas under pressure from said source to the liquid discharge line to lift a column of liquid therein up out of the well; valve control means responsive to fluid pressure existent in said second and third passages, respectively, for closing said valve when the pressure in the second passage decreases to a predetermined value and opening said valve when the pressure in the second passage reaches a predetermined ratio with respect to the pressure in the third passage; and a check valve in series with said valve for preventing movement of fluid from said second to said third passage while permitting movement of fluid from said third passage to said second passage.

34. A gas-lift pumping unit comprising a body member adapted for insertion in a well and defining a first passage for communication with the liquid in the well, a second passage for communication with a liquid discharge line extending out of the well, and a third passage for communication with a source of gas under pressure; means interconnecting said first and second passages for admitting liquid from the well into said liquid discharge line; means including a valve interconnecting said second and third passages for admitting gas under pressure from said source to the liquid discharge line to lift a column of liquid therein up out of the well, and valve control means therefor; said valve and valve control means comprising a valve seat defining a port interconnecting said second and third passages, a valve movable toward and away from said seat whereby said valve when seated exposes equal effective pressure areas to fluids in said second and third passages, respectively, pressure in said third passage tending to urge said valve against its seat, and additional means comprising a pair of members each having an outer face responsive to fluid pressure in said second passage for applying an opening force to said valve which is proportional to the fluid pressure in the second passage, one of said members exposing a face of a larger effective pressure area than the other, and fluid-tight means supporting said members and defining with said members a closed chamber, means coupling the faces of the said members together for simultaneous movement, and means operable by said members for opening said valve in response to pressure responsive movement of said member of larger face area.

35. A gas-lift pumping unit adapted for insertion in a well and defining a first passage for the entry of well fluid, a second passage for the discharge of well fluid to the surface, and a third passage for supplying gas under pressure to said

second passage, gas valve means interconnecting said second and third passages for admitting gas under pressure to discharge a column of liquid upwardly through said second passage, means interconnecting said first and second passages for passing fluid from said first passage to said second passage, and means responsive to fluid pressures existent in said second and third passages, respectively, for opening said gas valve when the pressure in the second passage reaches a predetermined ratio with respect to the pressure in the third passage, and closing said gas valve when the pressure in the second passage falls below a predetermined value.

36. A gas-lift pumping unit adapted for insertion in a well and defining a first passage for the entry of well fluid, a second passage for the discharge of well fluid to the surface and a third passage for supplying gas under pressure to said second passage, gas valve means interconnecting said second and third passages for admitting gas under pressure to discharge a column of liquid upwardly through said second passage, means interconnecting said first and second passages for passing fluid from said first passage to said second passage, and means responsive to fluid pressures existent in the second and third passages, respectively, for opening said gas valve when the ratio of the pressure in the second passage to the pressure in the third passage exceeds a predetermined value less than unity and closing said gas valve when the pressure in the second passage falls below a predetermined value, and a check valve inserted in series with said gas valve between said second and third passages for permitting fluid flow from said third passage to said

second passage and preventing fluid flow from said second passage to said third passage.

37. A gas-lift pumping unit adapted for insertion in a well and defining a first passage for the entry of well fluid, a second passage for the discharge of well fluid to the surface and a third passage for supplying gas under pressure to said second passage, gas valve means interconnecting said second and third passages for admitting gas under pressure to discharge a column of liquid upwardly through said second passage, liquid valve means interconnecting said first and second passages for passing well fluid from said first passage to said second passage, first means for intermittently opening said gas valve to admit gas from said third passage to said second passage to elevate a column of liquid in said second passage up therethrough and out of the well and closing said gas valve to permit a new column of liquid to form in said second passage, and second means responsive to fluid pressures in said second and third passages, respectively, for opening said liquid valve when the pressure in the third passage exceeds the pressure in the second passage and closing said liquid valve in response to increase of the pressure in the second passage to a value substantially equal to the pressure in the third passage, said second means also including means responsive to pressure in said first passage only when said liquid valve is closed tending to close said liquid valve in response to first passage pressure whereby the closing force on the liquid valve decreases as the valve opens, thereby causing the valve to open quickly.

GRANVILLE S. KNOX.
